UNITED STATES PATENT OFFICE.

GILBERT L. CROWELL, JR., OF ARLINGTON, NEW JERSEY, ASSIGNOR TO
THE DOMINICK & HAFF, OF NEW YORK, N. Y.

DESIGN FOR A HANDLE FOR SPOONS.

SPECIFICATION forming part of Design No. 28,092, dated December 28, 1897.

Application filed November 5, 1897. Serial No. 657,574. Term of patent 14 years.

To all whom it may concern:

Be it known that I, GILBERT L. CROWELL, Jr., a citizen of the United States, residing at Arlington, in the county of Hudson and State 5 of New Jersey, have invented and produced a certain new and original Design for a Handle for a Spoon or Similar Article, of which the following is a specification, reference being had to the drawings accompanying and forming a part of the same.

Figure 1 is a plan view of the obverse side of the handle of a spoon, illustrating my design. Fig. 2 is an enlarged cross-section on the plane *a a* of Fig. 1 and indicating that the 15 same design may be used on both faces of the handle.

The general outline of the handle is of the pandurate-spatulate order. The crown of the handle is ornamented by the acanthus-leaf 20 design A. The edges of this end of the handle bear the foliate borders B, of style similar to that of the said leaf design. The lower

end of the shank of the handle expands in outline and bears the divergent foliate spray C. D is a band of fluting or beading, which extends along and practically parallel to the outline edges of the shank and upper end of the handle of the spoon between the upper and lower leaf ornamentation. The included surface E is plain and slightly upwardly 30 curved, as shown in Fig. 2.

The essential features of the design are the leaf and foliate representation at the upper end of the handle and the spray at the end of the shank.

What is claimed as new is—

The design for a handle for a spoon or similar article, substantially as herein shown and described.

GILBERT L. CROWELL, JR.
